ERNEST TALBOT, OF LOWESTOFT, ENGLAND.

METHOD OF CONSTRUCTING PISTONS FOR FLUID-PRESSURE ENGINES.

1,233,726.

Specification of Letters Patent.

Patented July 17, 1917.

Application filed November 16, 1914. Serial No. 872,445.

To all whom it may concern:

Be it known that I, ERNEST TALBOT, a subject of the King of Great Britain, residing at Lowestoft, in the county of Suffolk, England, have invented certain new and useful Improvements in the Method of Constructing Pistons for Fluid-Pressure Engines, of which the following is a specification.

10 This invention relates to a method of constructing pistons for fluid pressure engines, of the type described and claimed in prior British Patent No. 13,273, A. D. 1910.

In pistons of this type it has been customary to form the gudgeon pin lugs or brackets integral with the trunk of the piston, either by casting or forming the trunk out of a forging and cutting away the surplus metal, or by pressing out of the wall 20 of the piston carriers for the lugs.

It is the object of the present invention to enable the trunk to be produced with its gudgeon pin lugs by stamping or pressing so that there is a minimum amount of material employed, and little or no metal has to be cut away in the construction of the lugs.

According to this invention, the trunk is so pierced that a large amount of metal is 30 displaced at two points, opposite to one another. This displaced metal is then shaped to form the lugs.

The accompanying drawings show two methods of carrying out this invention. In 35 Figures 1 and 2 of these the piston is represented in vertical section, and in Figs. 3 to 6 in side elevation in various stages of manufacture.

Like letters indicate like parts throughout 40 the drawings.

The piston in each case comprises a cap part A (omitted in Fig. 1) carrying the piston rings, and a trunk B which is enlarged at C at which part it makes contact 45 with the cylinder walls. The part B may be circular, or of any other suitable shape, and this part is eventually formed with lugs or brackets D, Figs. 4, 5 and 6, which carry the gudgeon pin.

50 The part B C is first formed to the preferred shape shown in Fig. 1 by stamping or other process. The flared metal joining the trunk B to the lower skirt C is then slit at two opposite points as indicated at F and G, forming T-shaped cuts. The metal is then forced from the interior outwardly

at two opposite points by suitable tools, such displacement extending into the length of B as far as may be necessary to give the proper diameter and length to the finished 60 piston pin bosses.

The preliminary operation leaves apertures E in the shape of arches having undivided connection with the trunk B and the flared metal joining B to C, but being 65 entirely open as to their back, front and base. The stage reached by these operations is shown by Figs. 2 and 3.

The walls of the arches are then pinched together and riveted (or otherwise secured) 70 as shown in Fig. 4.

In this way the piston pin lugs D can be produced integral with the trunk portion.

In the modified construction shown in 75 Figs. 5 and 6, the lugs are produced as before described and illustrated by Fig. 4 but instead of being riveted or otherwise secured at the abutting webs E', these webs (as shown in Fig. 5) are cut away so as to separate the circular portion of the lugs 80 from the flared metal.

The abutting edges of the lugs, the portion of the wall B, and the T-shaped cut in the flare, indicated by G, may then be brazed or welded together. In such case the 85 final lugs D are of simple cylindrical form, whereas in the construction illustrated by Figs. 2, 3 and 4, the lugs have the additional support of the integral webs joining the underside of the lugs to the flared portion connecting B and C. 90

By this means a light pressing or stamping can be used for the trunk of the piston, and the gudgeon pin lugs or brackets will still be formed integral with the trunk. 95

What I claim as my invention and desire to secure by Letters Patent is:—

1. The herein-described method of producing pistons for use as described which consists in first forming the cylindrical body 100 of the piston, slitting the body at two opposite points to form T-shaped cuts, forcing the metal from the interior outwardly to form diametrically opposite apertures having arches open at the rear, front and base, 105 and then pinching the walls of the arches together to form gudgeon pin lugs.

2. The herein-described method of producing pistons for use as described which consists in first forming the cylindrical body 110 of the piston, slitting the body at two opposite points to form T-shaped cuts, forcing

the metal from the interior outwardly to form diametrically opposite apertures having arches open at the rear, front and base, pinching the walls of the arches together to form gudgeon pin lugs, and then securing the said walls together.

In testimony whereof I have signed my

name to this specification in the presence of two subscribing witnesses.

ERNEST TALBOT.
